CLAIM

I claim, the ornamental design for a food container with three compartments, as shown as described.

DESCRIPTION

The patent or application file contains at least one drawing executed in color. Copies of this patent or patent application publication with color drawing(s) will be provided by the Office upon request and payment of the necessary fee.

4. Food container with three compartments

4.1 is a top perspective view of my new design for a food container with three compartments;

4.2 is a right view;

4.3 is a front view;

4.4 is a left view;

4.5 is a back view;

4.6 is a top view, and;

4.7 is a bottom view thereof.

The portions shown in red are excluded from protection and form no part of the claimed design.

1 Claim, 4 Drawing Sheets
